United States Patent Office

Des. 191,703
Patented Nov. 7, 1961

191,703

SCAFFOLD FOR USE WITH AIRCRAFT OR THE LIKE

Rodney K. Calvert, Dunwoody, and Charles B. Graham,
Jr., Marietta, Ga., assignors to Lockheed Aircraft Cor-
poration, Burbank, Calif.

Filed Nov. 7, 1960, Ser. No. 62,743

Term of patent 14 years

(Cl. D14—3)

FIG. 1

Des. 191,703

PAGE 2

Fig. 4

FIGURE 1 is a side elevational view of a scaffold for use with aircraft or the like, showing our new design in retracted position;

FIGURE 2 is a rear elevational view thereof;

FIGURE 3 is a front elevational view thereof; and FIGURE 4 is a side elevational view of the scaffold in extended position.

We claim:

The ornamental design for a scaffold for use with aircraft or the like, as shown.
